UNITED STATES PATENT OFFICE

IRA H. FREESE, OF CLARKSBURG, WEST VIRGINIA, AND DAVID C. EVANS, OF UNION-TOWN, PENNSYLVANIA, ASSIGNEES TO HAZEL-ATLAS GLASS CO., OF WHEELING, WEST VIRGINIA, A CORPORATION OF WEST VIRGINIA

DESIGN FOR A TUMBLER

Application filed April 11, 1930. Serial No. 35,230. Term of patent 7 years.

To all whom it may concern:

Be it known that we, IRA H. FREESE and DAVID C. EVANS, citizens of the United States, residing at Clarksburg, in the county of Harrison and State of West Virginia and Uniontown, in the county of Fayette and State of Pennsylvania, respectively, have invented a new, original, and ornamental Design for Tumblers, of which the following is a speci-

fication, reference being had to the accompanying drawing, forming part thereof.

The figure is a perspective view of a tumbler, showing our new design.

We claim:

The ornamental design for a tumbler, as shown.

IRA H. FREESE.
DAVID C. EVANS.
